(57) **CLAIM**

The ornamental design for a battery charger for automobile, as shown and described.

DESCRIPTION

FIG. 1 is a perspective view from the front side of a battery charger for automobile.

FIG. 2 is a front elevation view thereof.

FIG. 3 is a rear elevation view thereof.

FIG. 4 is a top plan view thereof.

FIG. 5 is a left side elevation view thereof; and,

FIG. 6 is a referential view showing use thereof.

The portion of the article shown in broken lines is for the purpose of showing environmental structure only and forms no part of the claimed design.
